UNITED STATES PATENT OFFICE.

CHARLES F. A. EDDY, OF GREENFIELD, MASSACHUSETTS.

RAILROAD-SWITCH.

SPECIFICATION forming part of Letters Patent No. 269,398, dated December 19, 1882.

Application filed June 22, 1882. (No model.)

To all whom it may concern:

Be it known that I, CHARLES F. A. EDDY, of Greenfield, in the county of Franklin and State of Massachusetts, have invented a new and Improved Railroad-Switch, of which the following is a full, clear, and exact description.

My invention consists of a latch and spring contrivance with the switch-bar and switch-rail, whereby the spring will set the switch for main line automatically when detached from the latch of the switch-bar.

It also consists of devices whereby the latch may be detached by the flange of the pilot-wheel of the locomotive, to enable it to be set for main line by the spring in advance of the wheels, when the locomotive is running along the main line from rear of the switch.

It also consists of a contrivance of devices in combination with the latch and spring device, whereby the attachment on the locomotive will unlatch the switch either way the locomotive may go, at the will of the engineer, all as hereinafter fully described.

Reference is to be had to the accompanying drawings, forming part of this specification, in which similar letters of reference indicate corresponding parts in all the figures.

Figure 1 is a plan view of a railroad-switch constructed according to my invention. Fig. 2 is a perspective view of the pilot-wheels of the locomotive and some of the attachments for unlatching the switch by the locomotive at the will of the engineer. Fig. 3 is a section of Fig. 2. Fig. 4 is a perspective view of a block for supporting one of the devices of the unlatching or tripping apparatus, and Figs. 5 and 6 are details of the latch device of the switch-rail in larger size. Fig. 7 is an enlarged section of Fig. 1 on line $\alpha\alpha$.

I make the switch-rail partly of a cast-iron plate, a , and partly of a steel point, b , which I rivet or bolt together, as at c , the casting being for the support of the steel point, and for securing it in position, and also for the connection of latch-block d' , and the point being for the wheels to run on, and to be taken off for repairs or removal when required. The casting is pivoted to the tie at d for turning, so as to set the switch for main line or siding, and it has a notch at e in the block d' for the latch f of the switch-bar g to engage it for set-

ting the switch by the eccentric h and lever i . Said casting also has a socket, j , in block d' for the end of a spring, k , which bears at its other end against the side of the rail m for resetting the switch to open the main line when it is unlatched. The guard-rail n is constructed with a cavity, o , for the latch-block d' of the switch-rail to swing into when set for the main line; and said guard-rail is constructed with an inclination toward rail m along the guard-rail, which is intended to bear the wheels of a train coming onto the main line from the siding, so as to shift the switch in case it is set for the main line sufficiently for the wheels to pass it onto the rail m .

In order to enable the pilot-wheels to trip the switch in case it is set for the siding when a train is required to pass along the main line to the right hand of the drawings, I have provided the pointed trip-lever p' to be pressed down at its pointed end p^2 to detach the latch f , said lever being pivoted to the side of the switch-rail b at q , and resting at its pointed end on the latch in such manner (Fig. 7) that the flange of the wheel passing over it will depress it and disengage the latch from notch e , and allow the spring k to set the switch for the main line. The lever p' will bear on latch f sufficiently distant from its hook-head to allow the switch-rail to swing back into cavity o without conflict with the head. This lever p' is designed to be so shaped along the upper edge at p^2 as to allow the switch-rail b to bear so closely against the side of main rail m as to prevent all danger of the wheel-flanges running between it and main rail when the switch is set for the train to run on it; at the same time it is fitted so closely to the switch-rail that no danger of striking the front of it when the switch-rail is open exists, even should the switch-rail fail to close into cavity o ; but the switch-rail is effectually prevented from failing to act, as described, by box o' of the guard-rail, which is to prevent any obstruction of said rail. The switch-rail has prongs a^2 , projecting under rail m , to prevent the switch-rail from rising. This arrangement is for tripping the switch only when the train is passing along the main line toward right hand of the drawings, which is always required in case the switch is set for the siding;

but it frequently happens that when the train is going in the other direction the switch, if set for the siding, is required to be tripped, and in this case it is necessary to trip it before the wheels arrive at the points of the switch-rails, which cannot be done as when going in the other direction. For this purpose I have provided a tripping-rail, p , in connection with the switch, and tripping-rollers q on the locomotive to actuate it. The rail p is located along rail m a little outside of it, and also a little higher, and pivoted at its ends, which are curved downward, as shown at s , by pivots t in slots u of blocks w over springs x in said slots. The rail p reaches a suitable distance each way from the switch-bar, and it crosses over said switch-bar, and is connected under bar g to another bar, b^2 , at c^2 , which bar is connected with eccentric d^2 , also worked by switch-lever i , and so arranged with respect to eccentric h that when the latter pulls switch-rail b up to main rail m by latch f rail p will be turned upright, as in Fig. 7, ready for tripping, the arrangement being such that as the switch-bar slides forward and backward switch-lever i will also swing the rail p on its pivots, turning it upright when said bar is shifted for setting the switch for the siding, and downward, as indicated by the arrow in Fig. 7 and in dotted lines in Fig. 1, when the switch is set for the main line, and the bar is shifted with it. A steady-pivot, e^2 , is arranged in the slotted arm f^2 , by which rail p is connected to bar b^2 , to prevent it from springing out of line laterally. This pivot is in line with pivots t , and the rail is capable of rising and falling on it. The rollers q on the locomotive are to strike this rail p on its curved ends s , and depress it so that it will detach the latch f ; and in order that they may pass rail p without unlatching the switch in case it is wanted to run onto the switch, said rollers are mounted on the cranks z of a shaft, a' , which is connected by an arm, b' , rod c' , and other suitable contrivances with a working-lever or a steam or compressed-air cylinder in the cab, whereby the engineer may set the rollers for tripping the switch, or swing them up when the switch is not to be tripped. By this means the switch is under the control of the engineer whichever way the train may be running. The latch-bar g is pivot-jointed at f' to facilitate the working of the latch; but it may be used without, the bar being capable of springing sufficiently. The shaft a' has stop-

lugs x' attached to it to rest against stops on the arms x^2 , by which it is supported to hold the cranks z in the right position for causing the rollers q to act on rail p ; and to prevent the rollers from being thrust back by contact with said rail, I have represented the arms x^2 as constructed together with and as part of the boxes x^3 of the front axle, which is a good arrangement; but they may be attached to any other part, as preferred.

It will be seen that this improved switch can be worked by the lever i without regard to the tripping device.

Having thus described my invention, what I claim as new, and desire to secure by Letters Patent, is—

1. The combination, with the switch-rail and the main rail m , of a latching switch-bar, f , and a sliding and spring-pressed block, d' , substantially as and for the purpose set forth.

2. The combination of trip-lever p' with the latch-bar f , spring k , and the switch-rail, substantially as described.

3. The guard-rail having cavity o , in combination with the switch-rail having latch-block d' , substantially as described.

4. The combination, with the rollers q on the locomotive, and means, substantially as herein shown and described, for operating the same, of a pivoted tripping-rail, p , substantially as and for the purpose set forth.

5. The combination of the tripping rail p , and rollers q on the locomotive, with the latch-bar f and with the switch-rail and spring k , substantially as described.

6. The tripping-rail p , pivoted in the slotted blocks w and on springs x , in combination with the latch-bar f and tripping-rollers q , substantially as described.

7. The tripping-rail p , arranged on pivots t , and connected to switch-lever i by bar b^2 , and eccentric d^2 , arranged with respect to eccentric h and switch-bar g , substantially as described.

8. The combination of prongs a^2 with the switch-rail b and the main rail m , substantially as described.

9. The combination of stay-pivot e^2 with tripping-rail p , mounted on pivots t , supported on springs x , substantially as described.
